UNITED STATES PATENT OFFICE

172,295

TOY CRADLE FOR DOLLS

William Medoff, Forest Hills, N. Y., assignor to
The Rexor Corporation, New York, N. Y., a corporation of New York

Application May 8, 1953, Serial No. 24,923

Term of patent 7 years

(Cl. D34—15)

To all whom it may concern:

Be it known, that I, William Medoff, a citizen of the United States, residing in Forest Hills, county of Queens, and State of New York, have invented a new, original, and ornamental Design for a Toy Cradle for Dolls, of which the following is a specification, reference being had to the accompanying drawing, forming part thereof:

Fig. 1 is a perspective view of a toy cradle for dolls, showing my new design;

Fig. 2 is a top plan view thereof, to a reduced scale;

Fig. 3 is a rear end elevational view thereof, to a reduced scale.

Fig. 4 is a front end elevational view thereof, to a reduced scale.

I claim:

The ornamental design for a toy cradle for dolls, as shown and described.
